BRAKE

Montgomery W. McConkey, South Bend, Ind.,
assignor to Bendix Brake Company, South
Bend, Ind., a corporation of Illinois

Application January 21, 1935, Serial No. 2,652

5 Claims. (Cl. 188—78)

This invention relates to brakes, and is illustrated as embodied in an internal expanding brake for an automobile.

An object of the invention is to utilize, in forming the shoes of the brake, rolled angle-section steel, cut and formed in segments adapted to have the brake lining secured thereto. Preferably these segments are cut from a rolled T-section steel ring, although many of the advantages of the invention can be secured by forming into arcuate segments pieces cut from a straight rolled angle-section, preferably of T-section.

One feature of the invention relates to providing a shoe formed of such a segment with separately-formed anchor-engaging means, such as a fitting shown as comprising two stampings permanently secured to the opposite sides of the web of the shoe.

Where used in an overlapping shoe brake, as illustrated, the anchor stampings of one shoe are deflected into engagement, and preferably welded or otherwise secured together to form a double-thickness strong anchor arm, while those of the adjacent shoe are spread apart to form a pair of spaced arms straddling the double-thickness arm.

The above and other objects and features of the invention, including various novel combinations of parts and desirable particular constructions, will be apparent from the following description of the illustrative embodiment shown in the accompanying drawing, in which:

Figure 1 is a vertical section through the brake, just inside the head of the brake drum, and showing the brake shoes in side elevation;

Figure 2 is a bottom plan view of the lower end of one of the two end shoes of the brake;

Figure 3 is a similar plan view of the end of the center shoe;

Figure 4 is a section on the line 4—4 of Figure 1 and shows the manner of connecting two of the shoes; and

Figure 5 is a section on the line 5—5 of Figure 1 showing the manner of anchoring two of the shoes.

The illustrated brake comprises a drum 42 rotating with the wheel (not shown), at the open side of which is arranged a support such as a backing plate 46. The brake is provided with any suitable return springs, steady rests, stops, and the like (not shown), and with operating means illustrated as a double cam 30.

The illustrated brake is of the three-shoe type. Two end shoes 90 and 92, and a center shoe 94, are arranged end to end, with shoes 90 and 92

actuated by the cam 30 and the center shoe 94 actuated by the end shoe 92.

Each of the shoes illustrated has a body portion formed of an arcuate segment of rolled T-section steel, having its stiffening web 26 arranged substantially in its center line. These segments are preferably cut from a rolled T section ring, as described in my Patent No. 1,875,081, dated August 30, 1932. However, many of the advantages of my invention can be secured by bending into arcuate segments, of the sort illustrated, straight pieces of rolled angle-section steel.

Each of the end shoes 90 and 92 has arranged at its lower end, and preferably welded or otherwise permanently secured thereto, a fitting shown as consisting of two steel stampings 96 and 98 engaging the opposite sides of the web 26 and formed at their ends with coaxial integral bearing sleeves adapted to embrace a pivot.

The fittings of shoe 92 straddle the end of the web of shoe 94 and are connected thereto by a floating pivot 82. The fittings of shoe 90 are mounted on a fixed anchor pivot 78 carried by the backing plate 46.

Shoe 94 has at its end, and preferably welded or otherwise permanently secured thereto, a fitting consisting of two steel stampings 100 engaging the opposite sides of its web 26, and preferably deflected into engagement with each other and welded or otherwise permanently secured together to form a double-thickness anchor arm.

These fitting members have at their ends integral coaxial bearing sleeves embracing an anchor pivot 80 carried by the backing plate. The above-described double-thickness arm 100 is straddled by the parts 96 and 98 of shoe 90. The anchor 80 passes through slots 97 in the members 96 and 98, and the anchor 78 passes through a similar slot 99 in the members 100, as is usual in three-shoe brakes of the type illustrated.

While one illustrative embodiment has been described in detail, it is not my intention to limit the scope of the invention to that particular embodiment, or otherwise than by the terms of the appended claims. This application is continuation in part of my Patent No. 1,875,081 dated August 30, 1932.

I claim:

1. A brake shoe having a stiffening web, in combination with a pair of separate parts secured to opposite sides of said web at its end and projecting beyond said end and deflected into engagement with each other to form a double-thickness pivot arm.

2. A brake comprising a pair of shoes, each in-

cluding an arcuate angle-section segment having a stiffening web, and one having centrally-arranged separately-formed anchor-engaging means secured to the end of its web and projecting beyond the end of said web, and the other having secured to and projecting beyond the end of its web a pair of separately-formed anchor parts straddling said means.

3. A brake comprising a pair of shoes, each including an arcuate angle-section segment having a stiffening web, and one having a pair of anchor-engaging members secured to the opposite sides of the end of its web and deflected into engagement with each other and projecting in the central plane of the shoe beyond the end of said web, and the other having secured to and projecting beyond the end of its web a pair of separately-formed anchor parts straddling said means.

4. A brake comprising a pair of shoes, each in-

cluding an angle-section segment having a stiffening web, and one having arranged at the opposite sides of said web at the end of the shoe a pair of stamped parts projecting beyond the end of said web and formed to straddle a pair of separately-formed anchor parts secured to the web of the other shoe and projecting beyond the end thereof.

5. A brake comprising a pair of shoes, each including an arcuate T-section segment, the stem of the T forming a stiffening web, one shoe having permanently secured to the opposite sides of its web at its end a pair of separate parts projecting beyond said end as spaced-apart and substantially parallel pivot arms, and the other shoe having a pair of separate anchor parts secured to its web and projecting beyond the end thereof to be received between said arms.

MONTGOMERY W. McCONKEY.

CERTIFICATE OF CORRECTION.

Patent No. 2,068,959.

January 26, 1937.

MONTGOMERY W. McCONKEY.

It is hereby certified that error appears in the printed specification of the above numbered patent requiring correction as follows: Page 1, second column, line 49, claim 1, strike out "having" and insert instead the words comprising an arcuate integral T-section segment, the stem of the T forming; and that the said Letters Patent should be read with this correction therein that the same may conform to the record of the case in the Patent Office.

Signed and sealed this 25th day of January, A. D. 1938.
